REFRIGERATOR CABINET OR SIMILAR ARTICLE

Anthony R. Costantini, Lafayette Hill, and Anthony Di Angelus, Manoa, Pa., assignors to Victory Metal Manufacturing Corp., Plymouth Meeting, Pa., a corporation of Pennsylvania

Filed Nov. 21, 1963, Ser. No. 77,520

Term of patent 14 years

(Cl. D67—3)

Fig. 1.

Fig. 2.

Fig. 3.

Fig. 6.

FIGURE 1 is a front perspective view of a refrigerator cabinet or similar article showing our new design;

FIGURE 2 is an end elevational view thereof;

FIGURE 3 is a rear elevational view thereof;

FIGURE 4 is an enlarged fragmentary elevational view of the grille;

FIGURE 5 is a vertical sectional view taken on line 5-5 of FIGURE 4; and

FIGURE 6 is a front elevational view of a modified form of the refrigerator cabinet or similar article shown in FIGURE 1, the ends and rear thereof being essentially the same as those of the cabinet shown in FIGURES 1 through 3.

We claim:

The ornamental design for a refrigerator cabinet or similar article, substantially as shown and described.
